UNITED STATES PATENT OFFICE.

THOMAS OWSTON WILTON, OF LONDON, ENGLAND.

FURNACE GRATE.

Application filed February 2, 1922. Serial No. 533,597.

To all whom it may concern:

Be it known that I, THOMAS OWSTON WILTON, residing at London, England, a subject of the King of Great Britain and 5 Ireland, have invented certain new and useful Improvements in Furnace Grates, of which the following is a specification.

This invention relates to furnace grates and fire bars, and particularly to the type 10 of furnace grates in which the fire bars are provided with conical or tapering apertures adapted to form passages or chambers when placed side by side, and with grooves or projections on the face which, when the fire 15 bars are so placed, form vents which permit air and steam to pass up to the surface of the grate.

The object of this invention is to provide 20 an improved fire bar and furnace grate with means for restricting the flow of air and steam to the rear parts of the grate so as to distribute the supply of air and steam to the furnace grate as may be required.

According to this invention, the passages 25 through the fire bars are suitably choked by placing baffle plates provided with suitably restricted apertures at suitable points along the grate, as may be required, so as to distribute the supply of air and steam to various parts of the furnace grate as may be desired. The apertures in the fire bars are 30 preferably tapered or coned so that each passage through the fire bars, instead of being cylindrical is constituted by a succession 35 of relatively sharp-edged constrictions.

Referring to the drawings filed herewith—

Fig. 1 is a longitudinal section of one form of furnace grate made in accordance with this invention;

Fig. 2 is an elevation of Fig. 1;

Fig. 3 is a plan of Fig. 1;

Fig. 4 is an elevation of one form of fire bar, showing this invention applied thereto.

aaa is the furnace front, *bbb* are tubes 45 adapted to receive the nozzles of the blowers, *ccc* are fire bars, *ddd* are apertures in the fire bars adapted to form passages in line with the tubes *bbb*, when the bars are placed side by side, *eee* are grooves on the face of

50 the fire bars to convey air and steam from the passages to the surface of the grate, *fff* are plates provided with holes *ggg* which are smaller than the apertures in the fire bars and so choke the passages.

h is the bridge, which may be hollow, 55 through which the blast may pass to heat the blast and cool the bridge.

Referring especially to Fig. 4, the individual fire bars are each provided with a plurality of apertures *d* extending through the thickness of the bars, said apertures being of greater diameter at one side of the bar than at the other, whereby each of said apertures form a substantially conical passage through the bar. The apertures are separated from each other by partitions, each of which is perforated at *h* to permit the passage therethrough of a clamping rod *j*. The grate is formed by assembling a number of these bars face to face, that is to say, the 60 face of one bar where the opening is smaller is placed adjacent the face of the next bar in which the opening is larger, the baffle plates *f* being placed at intervals between two adjacent bars. The tubes *b* are then 65 placed between the front plate *a* of the furnace and the first grate bar, said tubes being in alignment with the apertures *d* in said bar. The headed rods *j* are then inserted 70 through openings in the front plate *a* and the openings *h* in the series of bars, said rods being threaded at the inner ends to receive nuts *n* whereby the bars and tubes *b* are secured together, coil springs *m* being 75 provided on the rods to allow for expansion and contraction due to variations of temperature. It will thus be seen that the 80 apertures in the bars form passages from one end of the grate to the other, which 85 passages are formed by a succession of constrictions side by side, said constrictions being 90 adapted to give a sinuous form to the stream lines in the vicinity of the periphery of the said passages, thereby enhancing the flow of the air and steam through the grooves *e*, the vertical face of the constructions arresting the flow of air and steam and deviating it into the vents provided between the fire bars, while the sloping sides which follow immediately, induce the expansion of the flowing fluid into the hollow space each fire bar provides on the roof of the passages 95 therethrough.

Blowers are placed so as to enter the tubes *bbb* and air and steam pass along the 100 passages formed by the apertures *ddd* and through the grooves *eee* to the surface of the grate, the perforated plates *f* restricting 105

the flow of the air from one part of the passage to the next, so that by altering the position of the plates and the size of the holes *g*, the supply of steam and air can be permanently adjusted to suit any requirement.

Any fire bar can be removed by removing the nuts *n* on the rods and withdrawing the latter.

I am aware that it has been proposed to use unperforated baffle plates (or blank fire bars), located so as to divide the passage constituted by the apertures in the fire bars into several distinct chambers, each of which is supplied by a distinct blower or steam jet, for the purpose of distributing the air and steam supply to various parts of the grate, and I make no claim to this use and kind of baffle plate.

What I claim and desire to secure by Letters Patent is:—

1. A furnace grate, comprising a plurality of bars secured together, each of said bars having a plurality of apertures adapted to register with the apertures of adjacent bars

thereby to form a passage through the grate for conducting air and steam longitudinally thereof, and baffle plates placed at intervals between adjacent bars, said baffle plates having restricted apertures opening to the apertures of the bars. 25

2. A furnace grate, comprising a plurality of bars secured together, each of said bars having a plurality of apertures adapted to register with the apertures of adjacent bars thereby to form a passage through the grate for conducting air and steam longitudinally thereof, said apertures being of greater diameter at one side of the bar than at the other and each of said bars having a plurality of vertical grooves formed in its sides, 30 said grooves communicating with the apertures in the bars, and baffle plates placed at intervals between adjacent bars, said baffle plates having restricted apertures opening to the apertures of the bars. 35

In testimony whereof I have signed my name to this specification.

THOMAS OWSTON WILTON.
